UNITED STATES PATENT OFFICE

163,269

DOLL'S MINIATURE DRESSER

Theodore Friedman, New York, N. Y.; Martha Cowen executrix of Theodore Friedman, deceased

Application March 31, 1949, Serial No. 1,729

Term of patent 7 years

(Cl. D34—15)

To all whom it may concern:

Be it known that I, Theodore Friedman, a citizen of the United States of America, residing at New York, in the county and State of New York, have invented a new, original, and ornamental Design for a Doll's Miniature Dresser, of which the following is a specification, reference being made to the accompanying drawing, forming a part thereof.

Fig. 1 is a front view of a doll's miniature dresser showing my new design;

Fig. 2 is a top view thereof;

Fig. 3 is a side view thereof; and

Fig. 4 is a bottom view thereof.

I claim:

The ornamental design for a doll's miniature dresser, substantially as shown.

THEODORE FRIEDMAN.
